UNITED STATES PATENT OFFICE.

MORRIS HAYS, OF MONMOUTH, ILLINOIS.

WIRE-WORKING TOOL.

No. 852,836.

Specification of Letters Patent.

Patented May 7, 1907.

Application filed November 14, 1906. Serial No. 343,376.

To all whom it may concern:

Be it known that I, MORRIS HAYS, a citizen of the United States, residing at Monmouth, in the county of Warren and State of Illinois, 5 have invented new and useful Improvements in Wire-Working Tools, of which the following is a specification.

This invention is a wire working tool, designed particularly for joining or interlocking 10 wires by twisting, bending, curling or winding one about the other. It is also capable of use upon a single wire, for crimping, bending or straightening the same.

The invention is particularly adapted for 15 the manufacture of wire fences, and for the attachment of stay wires to line wires. The tool is not limited to this use, however, but may be used with advantage in making wire 20 articles or receptacles of any kind, such as racks, baskets, flower frames, trellises, screens, tree guards and the like, or any other woven wire structure.

The device has the advantage that it is 25 comparatively light, small, and cheap, and can be worked by one man or boy, and no expensive preparation or other appliances are necessary in the use thereof.

The invention is illustrated in the accompanying drawings, in which

30 Figure 1 is a top plan view thereof. Fig. 2 is a side view. Fig. 3 is a bottom view. Figs. 4 and 5 are views of opposite ends. Fig. 6 is a cross-section on the line 6—6 of Fig. 1. Fig. 7 is a view showing the device 35 applied in first position to twist a stay wire around a line wire. Fig. 8 is a similar view of the same in second position, or with the twist partially completed, the view being taken from the opposite side of the fence to 40 Fig. 7. Fig. 9 is a view showing the formation of a simple twist or splice. Fig. 10 is a view showing the manner of crimping a wire.

The device is made of metal, preferably of 45 cast iron, and has a hollow shell or body 6, which has the general outline or shape of a grip, and is of proper and sufficient size to be clasped in one hand while being worked, and it is shaped to fit the normal bend of the 50 palm and fingers so that a firm grip can be taken. On the under or bottom side the body has a longitudinal slot or opening 7, with irregular edges. The slot is wide enough to admit a wire of any ordinary size, whether barbed or not, and the body acts as

a shield and protection to the hand in working upon barbed or any other wire. 55

The ends of the shell or body are provided with openings 8 and 9, respectively, being formed by a continuation of the slot 7, so that when the device is applied to a wire the latter will pass through the slot and extend 60 through the openings. Thus the body practically surrounds or incloses the wire and can be moved along the same from one place to another, or turned or rotated thereon. 65

At one end, the device has projecting lugs or hooks 10 and 11. These are located on the under side of the body at one end of the slot 7 and they project substantially lengthwise with respect to the longitudinal axis of the 70 body, and are located on opposite sides of the opening 8. One hook or lug, 10, projects farther than the other, and has a more pronounced hook, which is presented upwardly or toward the top of the implement. At the 75 same end, the end wall 12 of the shell projects or inclines over or beyond the hook, and is provided with a curved edge 13 formed where the top of the shell joins the end wall. Also, at the same end, the edges of the slot 7 80 are indented on opposite sides as indicated at 14 and 15, said indentations being located just behind the hooks 10 and 11. At the opposite end of the body it is provided with a single hook or lug 16 located beside the opening 9 and at the end of slot 7. This hook projects lengthwise and turns upwardly beside the opening, and is particularly useful 85 for splicing.

In the use of the device, for a simple twist 90 or splice, as for attaching a stay wire to the top line wire of a fence, the shell is sleeved or placed over the line wire 17, as shown in Fig. 9, with the hook 16 engaging the stay wire 18 on the side opposite the line wire 17. Then, 95 by simply turning the body around, with the line wire 17 as a pivot, a simple twist is formed, as indicated at 19 in Fig. 9. It will be seen that the tool can be instantly slid along the line wire to the place for the next 100 stay wire. In splicing the ends of two wires, they are drawn together and crossed and held by a pair of pliers in one hand, and the present tool is applied first on one side and then on the other, with the hook 16 engaging 105 the free ends respectively, which are then twisted around the other wire.

For interlocking or connecting crossed

wires, the tool is placed on the line wire 20 on the side opposite to the stay 18, and the hook 10 is engaged behind the stay as shown in Fig. 7. The tool is then turned, causing 5 the hook 10 to take up a loop in the stay wire, as indicated at 21 in Fig. 8, and continued turn of the tool causes said loop to be wound around the line wire to form the lock. During the turn of the tool the inclined and overhanging edge 13 comes in contact with the stay wire in advance of the hook, and forces said stay wire off and out, as indicated at 22 in Fig. 8, so that the hook and loop will pass to form the lock without 15 catching in the stay wire.

The operation may be very quickly performed, and on its completion the tool can be instantly detached and passed on or down to the next place.

20 For crimping or bending wire, as shown for example in Fig. 10, the tool is placed on the strand so that the wire passes through the opening 8 and through one or the other of the indentations 14 or 15 under the heel of 25 the hooks 10 and 11. This gives two points of contact with the wire and enables the tool to be used as a lever, which will crimp or bend the wire to the extent desired.

Various other uses will suggest themselves 30 or will be learned by experience in the operation of the device, which contains, in a novel

and compact form, means to perform about all the operations necessary in making wire fences or other woven wire articles.

I claim:

1. A wire working tool comprising a hollow body having a slot along one side and openings in the ends of said body and at the ends of the slot, and a projecting hook beside one of said openings, said hook extending 40 endwise with respect to the axis of the body, and curved at its end laterally and outwardly in a direction at an angle to said axis.

2. A wire working tool comprising a hollow body having openings at opposite ends, 45 and a hook beside one of said openings, and also having an inclined projecting edge at the end, extending endwise beyond the hook.

3. A wire working tool comprising a hollow body having an opening at the end and a 50 slot in the side extending to said opening, an indentation in the edge of the slot, and a projection on said edge, between the indentation and the opening.

In testimony whereof I have signed my 55 name to this specification in the presence of two subscribing witnesses.

MORRIS HAYS.
